His Attorney.

UNITED STATES PATENT OFFICE.

ALOIS IHLN, OF BERLIN-CHARLOTTENBURG, GERMANY, ASSIGNOR TO GENERAL ELECTRIC COMPANY, A CORPORATION OF NEW YORK.

ARC LIGHT.

Application filed December 24, 1923, Serial No. 682,371, and in Germany May 5, 1923.

My invention relates to arc-lights in general and is especially adapted to the so-called tungsten arc type of light.

In tungsten arc-lamps with contact ignition the form of the electrodes at the point where the arc is found changes due to the transfer of matter in the arc from the cathode to the anode with the result that the necessary contact between the electrodes when the lamp is at rest is not always established. According to the invention, a satisfactory contact can be maintained between the electrodes regardless of the deformation of the anode resulting from the arc for the reason that when the lamp is put out, contact between the electrodes takes place at some other point than at the point where the arc is formed. According to my invention, it is also possible to cause the arc to change its position by suitably shaping the cathode or by turning one or both of the electrodes when they become separated at the time of ignition.

The means for accomplishing the foregoing and other useful ends are hereinafter more fully set forth and claimed, reference being had to the accompanying sheet of drawings. In the accompanying drawings, several forms of the device of my invention are shown. Fig. 1 shows in elevation one type of tungsten lamp of my invention; Fig. 2 is a top view of the electrodes shown on an enlarged scale; Figs. 3, 4 and 5 are top views of electrodes differing in type from those shown in Fig. 2.

The tungsten lamp shown in the drawings consists of a glass receptacle *a* of the well known glow light shape having a stem base *d* enclosing the lead-in wires *b* and *c*. The lamp is also provided with a rod-shaped cathode *g* supported by holders *e* and *f*. The cathode is best provided with a sleeve of thorium oxide *g'*.

Lamps of this general class are well known in the art and are usually filled with such gases as argon or a mixture of argon and nitrogen. The lamp may be operated under varying pressure but preferably under diminished pressure even as low as 15 mm.

The lamp is also provided with a spherical anode *h* held in place by the rod *i* in which rod a strip of bi-metal *k* is inserted. As shown in Fig. 2, the cathode *g* and the sleeve *g'* have each an elbow along the region *l*.

It is at this point that the anode *h* rests

against the cathode when the lamp is not burning. At the moment the current is turned on, the current is short-circuited by way of the electrodes *g* and *h* so that a heavier current is caused to flow than after the arc is established. The reason for this is that before the arc is started, the line voltage is only opposed by the resistor used in connection with the lamp, which resistor is not shown in the figure.

As soon as the strip of bi-metal becomes heated by the current flowing through it, the spherical anode *h* is drawn from the cathode and moved in the direction of the arrow parallel to the rod-shaped cathode *g* and *g'* until it arrives at a position similar to that of the dotted lines in which position it remains as long as the lamp is burning. It will be understood that the arc begins to form or is formed from the moment that the anode *h* separates from the cathode. As indicated in Fig. 4, the arc is thus maintained at some other point than the point of contact.

Referring to Fig. 2, it will be understood that the point of contact is between the anode *h* and the cathode at the elbow region *l* where the anode is shown in solid lines, whereas the point at which the arc is maintained is between the anode and the cathode at the point where the anode *h* is shown in dotted lines. A similar explanation applies to the construction shown in Figs. 3 and 5. In other words, the point of arc-over on the anode in a device similar to that shown in Fig. 2 may be at a point a great many degrees away from the point of contact. In some instances, it may be almost 180 degrees away from the point of contact. For this reason, the point of contact cannot be badly influenced by the arc so that even after the lamp has burned for a long period, a good contact is still preserved between the electrodes when the current is shut off. It will be understood that the abutment formed by the bend *l* at the cathode may also be brought about in any other suitable manner, for instance, by means of a thickening of a cross-pin.

Although the presence of oxides at the cathode facilitates the maintenance of the arc, the current flow at the contact on the other hand is better ensured when both contact points at the anode and at the cathode consist of better contact and smoother ma-

material such as tungsten. The design shown in Fig. 3 complies with this requirement and offers at the same time the advantage of a similar construction. In this form of design a piece of tungsten *m* which can be hemispherical, for instance, is pushed over the thorium oxide containing sleeve *g'* of the cathode *g* and it is against this piece that the hemispherical tungsten anode will rest when the lamp does not burn. When the current is turned on and the anode becomes separated from the cathode, the arc is formed between the thorium oxide containing sleeve *g'* and the anode surface about the point of contact. The tungsten body which is pushed over the sleeve may have any suitable shape and so may the anode.

In the type of construction shown in Fig. 4, the anode *h* lies on the straight part of the sleeve *g'*, but, when the current is turned on, the anode moves in the direction of the arrow as indicated by the dotted line, the direction of travel being along the line *n* sloping with respect to the cathode *g'*. The bend in the cathode in Fig. 4 is shown along the region *o*. Therefore, as the anode travels, the arc travels with it and settles at some point, such as the point *p*, for example. Thus, also in this case, the shape of the cathode insures that the anode, when the current is cut off from the lamp, shall engage the cathode at some point other than the point *p*.

In the construction shown in Fig. 5, the anode *h*, when the current is shut off, moves slantwise toward the rod-shaped cathodes *g* and *g'* which is straight, but then the anode *h* is made to rotate about its axis while it moves lengthwise. This is brought about by a suitable shape of the strip of bi-metal with which the holding stem is provided. The reverse operation takes place when the current is turned off; therefore, in this case also, the arc finally settles at a point on the anode surface other than the point at which the anode engages the cathode and other than that at which the ignition starts or takes place.

Instead of rotating the anode during the process of ignition or during the process of establishment of the arc with respect to the cathode, it is possible, if necessary, to rotate the cathode with respect to the anode in order that the permanent arc may be formed itself with other spots of the electrode surface than the spot of contact. This can be accomplished for example by having the bi-metal element *h* lying in a horizontal position, Fig. 1, instead of in a vertical position, as shown in said figure in which case the electrode *h*, instead of traveling in a straight line, as indicated by the dotted line, Fig. 4, will travel in an arc of a circle, thereby giving the electrode a rotating motion with respect to the electrode *g*. The same result

can be obtained by having one bi-metal element in a vertical plane as in Fig. 1, and one bi-metal element in a horizontal plane, in which case the bi-metal element in the vertical plane will cause the electrode *h* to travel, for example, in a direction parallel to the electrode *g*, whereas the bi-metal element in the horizontal plane will cause the electrode *h* to travel in a direction across the direction represented by the electrode *g*, thereby producing the rotating effect mentioned.

It will be understood that the bi-metal element referred to may be constructed of two dissimilar metals secured together, each having a coefficient of expansion different from the other. Bi-metal elements of this type are of course well known in the art.

The invention can be utilized in tungsten lamps having electrodes of any shape, for instance, spherical or hemispherical. In this case, care must be taken to insure a rotating motion of either or both electrodes when they become separated and at the time ignition takes place.

It will be understood that although I have illustrated specific forms of construction of my invention as required by the statutes, I do not wish to limit myself to the constructions shown inasmuch as variations will readily suggest themselves to those skilled in the art as a result of the disclosure in this specification.

What I claim as new and desire to secure by Letter Patent of the United States, is:—

1. In an arc lamp, a pair of electrodes normally in contact with each other, means for separating one of said electrodes from the other whereby an arc is started in the region of contact, said means also serving for continuing the movement of said electrode to draw the arc away from the region of contact on the other electrode toward another region of said other electrode and to maintain the arc in the new region, thus preventing rapid deterioration of said point of contact.

2. In an arc lamp, a pair of electrodes normally in contact with each other, means for separating one of said electrodes from the other whereby an arc is started in the region of contact, said means also serving for continuing the movement of said electrode to draw the arc away from the region of contact on the other electrode toward another region of said other electrode and to maintain the arc in the new region, thus preventing rapid deterioration of said point of contact, said means serving also to restore the electrode into contact at the original point when the current is cut off from the lamp.

3. In an arc lamp, an electrode, a second electrode normally in engagement with said first electrode, means for moving said sec-

ond electrode with respect to said first electrode to start an arc between the two electrodes in the region of contact, said means also serving for continuing the movement 5 of said electrode to draw the arc away from said region of contact on the first electrode, and to maintain the arc in a new region whereby the physical condition of said contact on the first electrode is prevented from 10 rapid alteration, said means comprising a

thermostatic element, the thermostatic element being so supported that after the second electrode has been moved a maximum distance from the first electrode, the second electrode continues its movement without increasing the distance between the two electrodes. 15

In witness whereof, I have hereunto set my hand this 30th day of November, 1923.

ALOIS IHLN.

ond electrode with respect to said first electrode to start an arc between the two electrodes in the region of contact, said means also serving for continuing the movement of said electrode to draw the arc away from said region of contact on the first electrode, and to maintain the arc in a new region whereby the physical condition of said contact on the first electrode is prevented from 10 rapid alteration, said means comprising a thermostatic element, the thermostatic element being so supported that after the second electrode has been moved a maximum distance from the first electrode, the second electrode continues its movement without increasing the distance between the two electrodes.

In witness whereof, I have hereunto set my hand this 30th day of November, 1923.

ALOIS IHLN.

Certificate of Correction.

Patent No. 1,640,450.

Granted August 30, 1927, to

ALOIS IHLN.

It is hereby certified that error appears in the printed specification of the above-numbered patent requiring correction as follows: Page 2, line 43, for the word "off" read *on*; same page, line 86, for the word "of" read *or*; and that the said Letters Patent should be read with these corrections therein that the same may conform to the record of the case in the Patent Office.

Signed and sealed this 11th day of October, A. D. 1927.
